UNITED STATES PATENT OFFICE.

HARRY FOREST GEIST, OF SUMTER, SOUTH CAROLINA, ASSIGNOR TO SPLITDORF ELECTRICAL COMPANY, OF NEWARK, NEW JERSEY, A CORPORATION OF NEW JERSEY.

IGNITION DEVICE.

1,271,155.

Specification of Letters Patent. Patented July 2, 1918.

Application filed February 15, 1918. Serial No. 217,836.

To all whom it may concern:

Be it known that I, HARRY FOREST GEIST, a citizen of the United States, residing at Sumter, in the county of Sumter and State 5 of South Carolina, have invented certain new and useful Improvements in Ignition Devices, of which the following is a specification, reference being had to the accompanying drawing.

10 The invention relates to new and useful improvements in ignition devices for internal combustion engines and more particularly to an ignition device of the make and break type, wherein the current is supplied 15 by a generator, the rotor or armature of which is operated intermittently and at the time of producing the spark.

An object of the invention is to provide 20 an ignition device of the above character with means for lightly holding the ignition points in contact when the parts of the generator are in normal idle position and with means for firmly pressing the ignition points into contact when the rotor or armature is 25 actuated.

A further object of the invention is to provide a device of the above character 30 wherein a spring is utilized for moving the ignition points toward each other and for holding the same in contact and wherein devices are provided for increasing the tension of the spring through the movement of the rotor or armature toward releasing position.

35 These and other objects will in part be obvious and will in part be hereinafter more fully disclosed.

In the drawings which show by way of 40 illustration one embodiment of the invention;

Figure 1 is a side view of an ignition device embodying my invention;

Fig. 2 is a view partly in section and 45 partly in side elevation, showing the trip lever, a portion of the springs for actuating the same, the electrodes and the supporting bracket therefor, with the trip lever in normal idle position;

Fig. 3 is a similar view but showing the 50 connection of the springs to the trip lever and also showing the trip lever moved to the point of release; and

Fig. 4 is a view similar to Fig. 3 but showing the trip lever released and thrown to 55 position for separating the ignition points.

The invention consists generally of an ignition device having a fixed electrode and a movable electrode carrying ignition points. The movable electrode is spring pressed so as to normally hold the ignition points in contact. Current is furnished to the ignition points by a generator of the oscillating type; that is, wherein the rotor or armature is actuated by means of a spring or springs through the aid of a trip lever and a push rod which operates upon the trip lever to store power in the springs and releases the same so that the rotor or armature may be moved through the stored power for providing a maximum current for ignition in proper timing with the movements of the piston in the cylinder. The movable electrode is operated for separating the ignition points in timing with the movement of the rotor or armature. The spring pressed means for moving the ignition points in engagement is so connected or associated with the trip lever for moving the rotor or armature, that the tension of the spring is increased as the armature is moved toward releasing position, so that the ignition points will be firmly pressed into contact at this time.

Referring more in detail to the drawings, I have shown my invention as embodied in 55 an ignition device which is supported by a bracket structure indicated at 1. This bracket is attached to the cylinder wall which is indicated at 2. Mounted in the bracket is a fixed electrode 3 and a movable 60 electrode 4. A movable electrode in the cylinder carries an arm 5 which supports an ignition point 6, which is adapted to coöperate with the ignition point 7 on the fixed electrode. These parts are of the usual construction and have only been shown more or less diagrammatically in the drawings. Current is supplied to the ignition points from a generator G, which is mounted on the supporting bracket 1. The generator is provided with a rotor or armature 8, on the outer end of which is a bifurcated arm 9. Pivotedly supported by the bracket 1 is a trip lever 10, which is provided with oppositely extending arms 11 and 12. A spring 13 is 65 connected to the arm 11 at its inner end and at its outer end to a pin 14 carried by the supporting bracket 1. A spring 15 is connected at its inner end to the arm 12 and at its outer end to a pin 16 carried by the 70

bracket 1. The arm 11 is connected to the bifurcated arm 9 on the armature and this connection is such that all movements imparted to the trip lever 10 will be likewise imparted to the rotor or armature of the generator. The trip lever is oscillated by a push rod 17, which is formed with a shoulder 18 adapted to be engaged in a notch 19 formed in the trip lever. The arm 20 of the trip lever as it is moved, engages the upper face of the push rod 17 and gradually forces the shoulder 18 out of the notch in the trip lever and thus releases the same. When the parts are in normal idle position as shown in Fig. 2, the springs 13 and 15 are substantially in alinement. When the trip lever is moved to the position shown in Fig. 3, these springs are moved out of alinement and power is stored in the springs, which is utilized when the trip lever is released to move the armature or rotor very rapidly, so as to produce an efficient current for ignition purposes although the speed of the engine may be very slow. The trip lever 10 is formed with an arm 21 having a cam face 22 which is adapted to make contact with a cam face 23 on an arm 24 fixed to the shank of the movable electrode. These cam faces 22 and 23 are normally out of contact when the parts are idle as shown in Fig. 2. When the trip lever is released, the momentum of the trip lever carries the springs past alinement as shown in Fig. 4, bringing the cam face 22 into contact with the cam face 23, which moves the movable electrode so as to separate the ignition points to produce the spark. The arm 24 is extended forwardly as indicated at 25. A spring 26 is connected at one end to the outer end of the arm 25 and at its other end to a lug 27 on the arm 20.

This spring 26 turns the movable electrode in a clockwise direction and this forces the movable ignition point toward the fixed ignition point and holds said ignition points in contact when the parts are in normal idle position as shown in Fig. 2. The spring is so proportioned that the ignition points are lightly held in contact at this time. When the trip lever is moved for storing power in the springs 13 and 15, the lug 27 is moved away from the outer end of the arm 25 and this increases the tension of the spring 26, so that the ignition points will be forced into contact with increasing pressure until the trip lever reaches the point of release. This tension of the spring will of course decrease as soon as the trip lever moves through the action of the springs 13 and 15 for generating current for ignition purposes. Not only will the tension of the spring decrease until the normal tension is reached, but as the parts through momentum, move to the position shown in Fig. 4, the tension of the spring will be decreased below the normal

tension when the parts are in idle position, so that when the cam face 22 strikes the cam face 23 for separating the ignition points, the tension of the spring is extremely light and very little power is necessary to separate the ignition points. It will thus be seen that I am able to use a spring which is very light and free working and thereby save in the power consumed in the movements of the ignition points relative to each other. Furthermore, by the use of this very light and free working spring, I am able to eliminate noise and also reduce to a minimum the wear on the parts, particularly the wear on the cam faces, which come into contact for moving the electrode. Excessive wear on these cam faces causes the time that the ignition points are open relative to the time of maximum current generation to vary and by reducing this wear, I thereby maintain the efficiency and extend the life of the ignition device.

It is obvious that minor changes in the arrangement of the parts and the details of construction may be made, without departing from the spirit of the invention as set forth in the appended claims.

Having thus described the invention what is claimed as new and what I desire to protect by Letters Patent is:—

1. An ignition device comprising ignition points, a movable electrode carrying one of said points, a generator, spring means associated with the generator, a trip lever connected to the spring means for operating the generator, means for moving the trip lever and for releasing the same, means whereby said trip lever when released actuates the movable electrode, spring means for normally holding the ignition points in contact, said spring means including devices whereby the tension of the spring is increased while said points are in contact and as the trip lever is moved toward releasing position.

2. An ignition device comprising ignition points, a movable electrode carrying one of said points, a generator, spring means associated with the generator, a trip lever connected to the spring means for operating the generator, means for moving the trip lever and for releasing the same, means whereby said trip lever when released actuates the movable electrode, a spring of relative light tension for normally holding the ignition points in contact and devices for increasing the tension of said spring between the times of separation of the ignition points.

3. An ignition device comprising ignition points, a movable electrode carrying one of said points, a generator, spring means associated with the generator, a trip lever connected to the spring means for operating the generator, means for moving

the trip lever and for releasing the same, means whereby said trip lever when released actuates the movable electrode, an arm carried by the movable electrode, an arm carried by the trip lever and a spring normally of relative light tension connecting said arms and holding the ignition points in con-

tact, said arms and spring being so disposed that a movement of the trip lever toward releasing position increases the tension of said spring.

In testimony whereof I hereunto affix my signature.

HARRY FOREST GEIST.
